UNITED STATES PATENT OFFICE

157,102

PORTABLE OIL PUMP AND TANK

Michael A. Tabet, Norfolk, Va., assignor to Tabet
Manufacturing Company, Incorporated, Norfolk,
Va., a corporation of Virginia

Application February 9, 1948, Serial No. 144,375

Term of patent 14 years

(Cl. D52—2)

To all whom it may concern:

Be it known that I, Michael A. Tabet, a citizen of the United States, residing at Norfolk, in the State of Virginia, have invented a new, original, and ornamental Design for a Portable Oil Pump and Tank, of which the following is a specification, reference being had to the accompanying drawings, forming part thereof.

In the drawings:

Fig. 1 is a perspective view of a portable oil pump and tank, showing my new design.

Fig. 2 is a plan view.

Fig. 3 is a rear elevational view.

Fig. 4 is a front elevational view.

Fig. 5 is a side elevational view.

The side of the portable oil pump and tank not shown in the drawings is the same in appearance as the side shown in Fig. 5.

The dominant features of my design reside in the portion shown in full lines.

I claim:

The ornamental design for a portable oil pump and tank, as shown and described.

MICHAEL A. TABET.
